DESIGN FOR A TOOL FOR REMOVING SLATE AND ASBESTOS SHINGLES

Bloomfield M. Joynes, Hampton, Va.

Application September 10, 1943, Serial No. 111,098

Term of patent 14 years

To all whom it may concern:

Be it known that I, Bloomfield M. Joynes, a citizen of the United States, residing at Hampton, in the county of Elizabeth City and State of Virginia, have invented a new, original, and ornamental Design for a Tool for Removing Slate and Asbestos Shingles, of which the following is a specification, reference being had to the accompanying drawing, forming part thereof,

Figure 1 is a top plan view of a tool for removing slate and asbestos shingles, showing my new design and

Figure 2 is a side elevational view thereof.

I claim:

The ornamental design for a tool for removing slate and asbestos shingles, as shown.

BLOOMFIELD M. JOYNES.
